UNITED STATES PATENT OFFICE.

NATHAN HUNT, OF SALEM, OHIO, ASSIGNOR OF ONE-HALF TO THE BUCK-EYE ENGINE COMPANY, OF SAME PLACE.

ECCENTRIC AND STRAP FOR STEAM-ENGINES.

SPECIFICATION forming part of Letters Patent No. 275,659, dated April 10, 1883.

Application filed February 12, 1883. (No model.)

To all whom it may concern:

Be it known that I, NATHAN HUNT, of Salem, in the county of Columbiana and State of Ohio, have invented certain new and useful Improvements in Eccentrics and Straps for Steam-Engines, of which improvements the following is a specification.

The object of my invention is to perfect the operation of eccentrics and their straps, more particularly as employed for actuating the valves of steam-engines, by obviating the undue pressure and friction resultant upon disturbance of the normal alignment of the eccentric-rod; to which end my improvements consist in an eccentric having its wearing-surface in the form of a spherical zone; also, in an eccentric-strap having its internal surface spherically recessed or bored out; also, in the combination of an eccentric and an eccentric-strap the surfaces of contact of which are at all points correspondingly spherical.

The improvements claimed are hereinafter more fully set forth.

In the accompanying drawings, Figure 1 is a side view, in elevation, of an eccentric and eccentric-strap embodying my invention; Fig. 2, a horizontal central section through the same, and Fig. 3 a view in elevation of the smaller section of the eccentric as seen from the top.

My improvements are herein illustrated as applied to a split or divided eccentric, A, composed of two sections, 1 2, but, as will be obvious, are equally applicable to eccentrics formed in a single piece. The strap B is, as usual, composed of two sections, 3 4, connected by bolts *b* and nuts *b'*, and the eccentric-rod C is connected to the section 3 by screw-threads and a nut, *c*. As heretofore constructed, the wearing-surface of the eccentric and the corresponding surface of the strap have been made either cylindrical or with a curvature the center of which does not coincide with the geometrical axis of the eccentric. In either of such cases proper wearing-contact is possible only during the perfect normal alignment of the eccentric-rod, and any disturbance of or variation therefrom tends to concentrate the

pressure and friction due to the performance of the functions of the parts upon limited portions of the wearing-surfaces, thereby causing 50 heating and unsatisfactory performance in other respects.

In the practice of my invention I form the wearing-surface *a* of the eccentric as a spherical zone by turning it to a radius of peripheral curvature, *x*, the center of which coincides with the geometrical axis *y y* of the eccentric, and I recess or bore out the strap B, so that its wearing-surface *b'* shall present throughout a corresponding spherical curvature. The 60 width of the wearing-surface of the eccentric is such as to admit of clearance between the eccentric-strap and the flange or collar *a'* of the eccentric, thereby permitting such movement of the strap upon the eccentric about the 65 center of the curvature of the wearing-surfaces as may be occasioned by variations of the eccentric-rod C from its true alignment, in any and all of which variations the frictional relation of the wearing-surfaces one to the other 70 will remain undisturbed, and cramping, binding, or unequal friction at different points is effectively prevented.

Disclaiming broadly an eccentric or strap having a curved wearing-surface, I claim as 75 my invention and desire to secure by Letters Patent—

1. An eccentric having its wearing-surface in the form of a spherical zone—that is to say, of a peripheral curvature the center of which 80 coincides with the geometrical axis of the eccentric.

2. An eccentric-strap which is internally recessed or bored out to a curvature the center of which coincides with its geometrical axis. 85

3. The combination, substantially as set forth, of an eccentric and an eccentric-strap the wearing-surfaces of which are at all points of corresponding spherical curvature.

NATHAN HUNT.
